UNITED STATES PATENT OFFICE.

DAVID F. VAUGHAN, OF HADDONFIELD, NEW JERSEY.

RAILWAY-FROG.

SPECIFICATION forming part of Letters Patent No. 682,863, dated September 17, 1901.

Application filed April 2, 1901. Serial No. 54,026. (No model.)

To all whom it may concern:

Be it known that I, DAVID F. VAUGHAN, a citizen of the United States, residing at Haddonfield, Camden county, State of New Jersey, have invented certain new and useful Improvements in Railway-Frogs, of which the following is a full, clear, and exact description, reference being had to the accompanying drawings, of which—

10 Figure 1 is a plan view of a railway-frog in which my invention is embodied. Fig. 2 is a section on line $\alpha\alpha$, Fig. 1. Fig. 3 is a plan view of the filling-piece and supplemental wing-rails detached. Fig. 4 is a similar view 15 of a modification of the filling-piece, in which the frog-point, as also the supplemental wing-rails, are integral with said piece. Fig. 5 is a section similar to Fig. 2, but in which the said modification is substituted for the 20 form shown in Figs. 1, 2, and 3. Fig. 6 is a section similar to Fig. 2, but in which the supplemental wing-rails are made separate from the filling-piece. Fig. 7 is a plan view of the said supplemental wing-rails detached.

25 The object of this invention is to provide a railway-frog capable of withstanding the wear and tear usually resulting from the passage over the open throat or flangeway of the frog of the locomotive and car wheels.

30 The leading feature of the invention relates to what I shall term "supplemental wing-rails" of hard or hardened metal secured along the inner sides of the usual wing-rails adjacent to the sides of the point of the frog, 35 the said supplemental rails forming a bearing for the car-wheels and their inner sides forming, with the sides of the point of the frog, the usual flangeway or throat, whereby certain advantages are obtained, as herein- 40 after mentioned.

In carrying out my invention, reference 45 being had first to Figs. 1, 2, and 3 of the accompanying drawings, I form the point 1 of the frog by the converging track-rails 2 3 in the usual way, made of the ordinary style or pattern of rail; but instead of bending the wing-rails 4 so that their inner sides will form part or all of the channel or flangeway and bending their free ends outwardly to form a 50 wide entrance, as is usually done, I bend said rails outwardly in advance of the frog-point to an unusual extent, thus making a throat

or space between the rail and the point of abnormal width, which space extends from the toe of the point to the free end of the outwardly-bent portion of the rails and which is reduced to the usual width by the supplemental wing-rails shortly to be described, as seen in Fig. 1.

55 5 is a block or plate, which I shall term the "filling-piece," that is tapered to correspond with the taper of the wing-rails 4 and whose sides are adapted to fit against the webs of the wing-rails, respectively, and against the under side of the heads of the rails and the upper side of the flanges or feet of the rails, as seen in Fig. 3. This filling-piece extends past the point of the frog a suitable distance in both directions. It has a longitudinal slot 6 at its wider end, adapted to receive the webs of the converging track-rails 2 3, while the point 1 extends over and rests upon the filling-piece. Rising from the top of the piece, adjacent to the sides thereof, are what I have termed the "supplemental wing-rails" 75 7, whose upper surfaces are substantially even with those of the wing-rails, as seen in Fig. 2. The inner sides of these supplemental wing-rails are substantially parallel with the sides, respectively, of the point and of 80 the said track-rails 2 3, forming the usual flangeway 8, as shown. The width, outside to outside of said supplemental wing-rails at the widest end is substantially equal to the width between the heads of the wing-rails 4; 85 but the width increases relatively toward the narrow end, and the inner side of each of the wing-rails 4 is correspondingly cut away or planed off to let in that part of the supplemental wing-rails, the object being to have 90 the inner sides of the end portion of the latter in front of the point in line with the side of that part of the wing-rails and at the same time to have the necessary width or body to the metal at that place. The supplemental 95 wing-rails are bent or curved outwardly at 9, as shown, in order to provide a wide flangeway at that end to insure a safe entrance of the flanges of car-wheels. I make the filling piece or block 5 of hardened steel or other suitable hard metal or the supplemental wing-rails only may be hardened, the object being to have a material that will withstand 100 the shocks and wear and tear incident to

heavy traffic where the wheels of cars cross the open flangeway of the frog. The parts are assembled as seen in Figs. 1 and 2, being secured together by means of through-bolts 10.

5 It will be obvious that the wheels of cars passing in either direction across the open flangeway adjacent to the point of the frog will bear upon one of the supplemental wing-rails, also the wheel flanges entering the 10 flangeway between the latter and the frog-point.

I sometimes make the point 1 integral with the filling-piece, as illustrated in Figs. 4 and 5, in which case the pointed end of the track-rail 2 will be correspondingly cut off, so that 15 when entered in the slot 6, as before mentioned, the end thereof will be flush with the contiguous end of the point.

The form of the device shown in Figs. 6 and 20 7 differs from the form shown in Figs. 1, 2, and 3 only in that the supplemental wing-rails instead of being an integral part of the filling-piece are made separate and bolted together with the other parts.

25 I do not claim to be the first to use in a railway-frog a block or section of hard or hardened metal secured to the side of a wing-rail and adapted to form a durable bearing for the wheels of cars passing over the frog; but 30 my construction hereinbefore described enables me to produce a frog of the kind mentioned which may be more readily and cheaply made than any other with which I am acquainted. It also obviates the necessity of 35 cutting away and thus weakening the foot-flanges of the wing-rails or of the point-forming rails and also the bending outwardly of the free end of the wing-rails to form the wide entrance to the flangeway.

40 My invention is applicable to that kind of railway-frog in which one of the wing-rails is fixed and the other laterally movable. In such frog the supplemental wing-rail would be used only in connection with the fixed 45 wing-rail.

Having thus described my invention, I claim as new and desire to secure by Letters Patent—

1. The combination in a railway-frog, of 50 the point, the wing-rail bent outwardly in advance of said point to an abnormal extent, to form a space of abnormal width between the side of said rail and the side of the point, said space extending from the toe of the point to 55 the free end of the outwardly-bent portion of the rail, the filling-piece, the hard-metal supplemental wing-rail secured to said filling-piece and fitted to the side of the head of said wing-rail, and having its inner side substantially parallel with the side of the point, and forming, with the latter, the flangeway, substantially as and for the purpose set forth.

2. The combination in a railway-frog, of 60 the point, the wing-rail bent outwardly in advance of said point to an abnormal extent, to form a space of abnormal width between the

side of said rail and the side of the point, said space extending from the toe of the point to the free end of the outwardly-bent portion of the rail, the filling-piece, and the hard-metal 70 supplemental wing-rail integral with the latter and fitted to the side of the head of the wing-rail, and having its inner side substantially parallel with the side of the point, forming with the latter, the flangeway, as and for 75 the purpose set forth.

3. The combination in a railway-frog, of the point, the wing-rail, bent outwardly in advance of said point to an abnormal extent, to form a space of abnormal width between 80 the side of said rail and the side of the point, said space extending from the toe of the point to the free end of the outwardly-bent portion of the rail, the filling-piece, the hard-metal supplemental wing-rail fitted to 85 the side of the head of said wing-rail, and having its inner side parallel with the side of said point, and having also its wider end bent or curved outwardly toward said wing-rail, and separated from the said point to 90 form the flangeway, as and for the purpose set forth.

4. The combination in a railway-frog, of the convergent track-rails the filling-piece having the slot adapted to receive the webs of 95 the converging end portion of said track-rails, the point integral with said filling-piece, the divergent wing-rails bent outwardly, in advance of said point to an abnormal extent to form spaces of abnormal width between 100 the sides respectively of said wing-rails and the sides respectively of said point, said spaces extending from the toe of the point to the free ends of the outwardly-bent portions of the wing-rails, respectively, the supplemental wing-rails also integral with said piece, and fitted to the sides of the heads of the wing-rails, and having their inner sides substantially parallel with the sides of the point, forming with the latter the flangeway, 110 substantially as and for the purpose set forth.

5. In a railway-frog, the combination of the point, the wing-rail bent outwardly in advance of the said point to an abnormal extent, to form a space of abnormal width between the side of said rail and the side of the point, which space increases gradually in width from the toe of the point to the free end of the outwardly-bent portion of the rail, the filling-piece, the hard-metal supplemental 115 wing-rail secured to said filling-piece and fitted to the side of the head of said wing-rail, and having its inner side substantially parallel with the side of the point, and forming, with the latter, the flangeway, substantially as and for the purpose set forth.

6. In a railway-frog, the combination of the supporting-rails with a hard-metal body which fits into the sides of the said supporting-rails, and constitutes the principal part 130 of the frog, and is formed with a groove which is divided into two grooves by a point,

the said grooves being flared out laterally at the end, substantially as described.

7. In a railway-frog, the combination of the supporting - rails with a hard - metal body 5 which fits into the sides of the said supporting - rails, and constitutes the principal part of the frog, and is formed with a groove which is divided into two grooves by a point, the said grooves being flared out laterally at the end, 10 and the supporting-rails being extended be-

yond the flared-out ends of the grooves, substantially as described.

In testimony whereof I have hereunto affixed my signature this 29th day of March, A. D. 1901.

DAVID F. VAUGHAN.
